DESIGN FOR A HAT

Elsa Schiaparelli, New York, N. Y.

Application September 21, 1940, Serial No. 95,275

Term of patent 3½ years

To all whom it may concern:

Be it known that I, Elsa Schiaparelli, a citizen of the Republic of France, residing in city of New York, county of New York, and State of New York, have invented a new, original, and ornamental Design for a Hat, of which the following is a specification, reference being had to the accompanying drawing, forming part thereof.

Fig. 1 is a front view of a hat showing my new design.

Fig. 2 is a rear view thereof.

Fig. 3 is a rear view showing the ends in open position.

I claim:

The ornamental design for a hat, as shown.

ELSA SCHIAPARELLI.
